DESIGN FOR A TEXTILE FABRIC

Charles A. Lasky, Leonia, N. J., assignor to Cela-nese Corporation of America, a corporation of Delaware

Application June 6, 1936, Serial No. 63,071

Term of patent 14 years

To all whom it may concern:

Be it known that I, Charles A. Lasky, a citizen of the United States, residing at Leonia, in the county of Bergen, State of New Jersey, have invented a new, original, and ornamental Design for a Textile Fabric, of which the following is a specification, reference being had to the accompanying drawing, forming part thereof.

In the accompanying drawing:

The figure is a plan view of a piece of textile fabric embodying my new design.

I claim:

The ornamental design for a textile fabric substantially as shown.

In testimony whereof, I have hereunto subscribed my name.

CHARLES A. LASKY.
